UNITED STATES PATENT OFFICE.

JOSEPH GIULIANA, OF NEWARK, NEW JERSEY.

VALVE FOR PLAYER-PIANOS AND THE LIKE.

1,208,138.

Specification of Letters Patent.

Patented Dec. 12, 1916.

Application filed January 25, 1916. Serial No. 74,084.

To all whom it may concern:

Be it known that I, JOSEPH GIULIANA, a citizen of the United States, and a resident of Newark, in the county of Essex and State 5 of New Jersey, have invented certain new and useful Improvements in Valves for Player-Pianos and the like, of which the following is a specification.

The objects of this invention are to provide 10 a valve for player pianos which will hold its adjustment; to positively prevent the valve disks from slipping longitudinally of the stem; to accommodate variations in the thickness of valve disks employed, to 15 permit adjusting the disks readily upon the stem; to secure simplicity of construction and operation and to obtain other advantages and results as may be brought out in the following description.

20 Referring to the accompanying drawings in which like numerals of reference indicate the same parts throughout the several views, Figure 1 is a central section through the valve mechanism of a player piano showing 25 my improved valve therein, and Fig. 2 is an enlarged view of said valve shown in Fig. 1, partly in section.

In the specific embodiment of the invention illustrated in said drawings the reference 30 numeral 1 indicates a valve inclosure suitably hollowed out to provide a plurality of chambers 2, 3, 4 as is usual and well known in the art. The middle chamber 3 is in communication with a suitable suction 35 pump (not shown), as by tube 5, and is separated from one end chamber 2 by a flexible diaphragm 6. A tube 7 connects this chamber 2 with the tracker bar (not shown) in any customary or preferred manner, there 40 being also a bleed or vent hole 8 between these two chambers. A centrally apertured head 9 divides the opposite end chamber 4 from the middle chamber 3, and opposite the aperture in said head is a similar aperture 45 10 in the end wall 11 of the valve inclosure 1 opening to the atmosphere. A valve stem 12 extends through this end chamber 4 with its one end 13 projecting outside of the valve inclosure through the 50 aperture 10 and its other end 14 projecting into the middle chamber 3 and secured in any suitable manner to the diaphragm 6. Preferably a guiding bridge 15 is provided at the inner end of the chamber 4 for the 55 end of the stem to slide through, and the

other end 13 of the stem is similarly guided by a finger 16 carried by the valve inclosure. The middle part 17 of the stem or part between the ends 13, 14 is slightly greater in diameter than the diameter of one 60 or both of said ends, and is screw threaded. Obviously the length of this enlarged and threaded portion must be enough shorter than the distance between the guiding bridge and finger so as not to interfere with the 65 necessary reciprocation of the stem.

Upon the threaded portion of the stem are screwed a pair of sleeves 18, 18 each having an outwardly projecting shoulder 19 preferably at the end of the sleeve toward 70 the other sleeve. Suitable valve disks 20 are mounted upon the sleeves seating laterally against the shoulders 19 which prevent said disks from becoming displaced past the same. Preferably, the sleeves are screw 75 threaded on their outside or exteriorly as well as interiorly, as shown, and upon the exterior threads are screwed clamping rings or nuts 21. Obviously, the disk or disks carried by each sleeve may be clamped securely 80 between the shoulder 19 and nut 21, but preferably the nut is left loose enough so as to permit a slight movement of the valve disk which may therefore seat freely. It may be noted in this connection that should the 85 disks be of less thickness than shown, or even of somewhat greater thickness, the same may be properly held by the nut 21, and, where a plurality of thicknesses are employed to make up one of the disks, they 90 cannot become separated in use or during adjustment, but remain intact and as a unit.

In operation, it will be understood that the valve disks are adjusted upon the stem so as to allow a certain longitudinal movement of the stem. As shown in Fig. 1 the stem is slid so as to move the valve away from the end wall of the chamber 4 and admit air from the atmosphere to the chamber and thence to a pouch or bellows 22 allowing the bellows to distend. As atmospheric pressure is admitted from the tracker bar to the opposite end chamber 2, the diaphragm bulges toward the central chamber in which there is less pressure and slides the 95 stem outwardly thus operating to close the aperture 10 and open the aperture connecting chamber 4 with the middle chamber 3. Thereupon the air is exhausted partially from said chamber and bellows which closes, 100 105 110

and so on. Obviously the valve will move back or forward quickly and with considerable force, but by the construction of parts as shown, the valve disks cannot slide under 5 the constant knocking, are loose enough to seat properly, and are at the same time readily adjusted.

Having thus described the invention, what I claim is,

- 10 1. A valve for player pianos and the like comprising a stem having a threaded portion, a sleeve screw threaded interiorly adapted to be screwed on said threaded portion of the stem, and means for holding a 15 valve disk on said sleeve whereby the disk is prevented from slipping on said stem but may be adjusted with respect thereto.
- 20 2. A valve for player pianos and the like comprising a stem having a threaded portion, a sleeve threaded interiorly and exteriorly adapted to be screwed on said threaded portion of the stem, said sleeve having a shoulder, and a nut adapted to be screwed

upon the sleeve and hold a valve disk thereon between said nut and shoulder.

25

3. A valve for player pianos and the like comprising a stem having end portions adapted to be slidably guided and having a middle threaded portion, a sleeve threaded interiorly and exteriorly adapted to be 30 screwed on said threaded portion of the stem, said sleeve having a shoulder, and a nut adapted to be screwed upon the sleeve and hold a valve disk thereon between said nut and shoulder.

35

4. A valve for player pianos and the like comprising a stem having a threaded portion, a pair of sleeves threaded to screw onto said stem, said sleeves being exteriorly threaded and having shoulders at their adjacent ends, valve disks on said sleeves seating laterally against said shoulders, and nuts screwed onto said sleeves for retaining the disks thereon.

40

JOSEPH GIULIANA.
